UNITED STATES PATENT OFFICE.

JOHN J. MEEHAN, OF DENVER, COLORADO.

RAZOR-SHARPENING DEVICE.

942,731.

Specification of Letters Patent. Patented Dec. 7, 1909.

Application filed July 2, 1908. Serial No. 441,537.

To all whom it may concern:

Be it known that I, JOHN J. MEEHAN, a citizen of the United States, residing in the city and county of Denver and State of Colorado, have invented certain new and useful Improvements in Razor-Sharpening Devices; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in devices for sharpening razors, my object being to provide a device of this class which shall be specially adapted for use in sharpening double edged blades of the Gillette or other similar types.

My improved construction includes a casing in which is journaled a rock shaft or spindle, around which the flexible stropping device passes. Also journaled in this casing is a second rock spindle which forms a holder for the razor blade. The two rock spindles are connected on the outside of the casing in such a manner that when the spindle which is acted upon by the strop, is actuated by a pull of the strop in one direction, a corresponding movement is imparted to the spindle carrying the blade to be sharpened, thus bringing the opposite edge of the blade into operative engagement with the strop for sharpening purposes. Provision is also made for normally retaining the blade-carrying spindle in a position whereby both of its edges are out of contact with the runs of the stropping device, thus obviating the possibility of cutting the latter while reversing its running movement.

Having briefly outlined my improved construction, I will proceed to describe the same in detail, reference being made to the accompanying drawing in which is illustrated an embodiment thereof.

In this drawing, Figure 1 is a top plan view of my improved device. Fig. 2 is a side view of the same looking in the direction of arrow 2, Fig. 1. Fig. 3 is a sectional plan view of the device cutting the casing and the strop, the two spindles also being shown partly in section. Fig. 4 is a section taken on the line 4-4, Fig. 1, looking in the direction of the arrow. Fig. 5 is a section taken on the line 5-5, Fig. 1,

the parts being shown on a larger scale. Fig. 6 is a side view, similar to Fig. 2, the parts, however, being shown on a larger scale and in different relative positions. 60 Fig. 7 is a detail view of the split sleeve for receiving the blade-holding spindle. Fig. 8 is a view of the same looking in the direction of the arrow in Fig. 7. Fig. 9 is a detail view of the blade-carrying spindle. 65 Fig. 10 is a similar view with the blade in place, the spindle being shown on a smaller scale. Fig. 11 is a similar view showing a slightly modified form of the blade. Fig. 12 is a detail view of the spring for normally retaining the blade in an intermediate position, and parallel, or approximately so, with the two runs of the strop.

The same reference characters indicate the same parts in all the views. 75

Let the numeral 5 designate a casing provided with upper and lower separated walls 6, whose adjacent extremities are connected by side walls 7 and 8. Journaled in these side walls near one end of the casing is a rock spindle or roller 9 having one extremity solid, as shown at 10, to facilitate the fastening of a crank arm 12 by means of a screw 13. This arm 12 is provided with a pin 14 which passes through a slot 15 formed in one extremity of an arm 16 secured to one end of a spindle 17 by a screw 18. This spindle is journaled in the opposite side walls 7 and 8 of the casing, and is split on opposite sides, as shown at 19, to 80 receive the protruding portions of the razor blade 20, when the latter is mounted upon its holding pin 21, the said pin being inserted in the hollow spindle as indicated in the assembled views. This blade-holder, 85 as shown in the drawing, is flattened on one side, as shown at 22, and from this flat side protrude removable studs 23, adapted to pass through openings 24 formed in the blade 20. By making the studs 23 removable and providing the holder 21 with a series of threaded recesses 25, the position of the studs may be changed to cause them to pass through openings formed in blades of different manufacture. Moreover, these 90 studs may be placed at opposite extremities of the blade (see Fig. 11), the blade in this event being provided with V-shaped recesses 26. One extremity of the blade-holder 21 is provided with a milled head 105 27 which protrudes from the casing on one side. This protruding head facilitates the 110

removal and insertion of the blade-holder in the hollow spindle 17 journaled in the casing, as aforesaid.

The hollow spindle 17 is provided at one extremity with a lip 28, which projects outwardly therefrom, occupying a position beyond the adjacent extremity of the razor blade when the blade-holder is inserted in the said spindle. This blade is engaged on opposite sides by the laterally projecting extremities 29 of a coil spring 30, the latter being mounted upon and made fast to a screw pin 31, secured to one side of the casing. The coil must be locked upon the screw pin by solder, or otherwise, to prevent it from turning bodily thereon. In this event the opposite opposing arms 29 of the spring are both under tension, and if their movement were not arrested by the pin 28, they would occupy a crossed position. Hence, when the spindle 17 is turned in one direction, the movement of the pin 28 is resisted by the tension of one of the spring arms 29; and hence, as soon as the power acting to turn the spindle ceases to act, the spring arm returns the spindle to its normal position. This happens regardless of the direction of the spindle's turning movement.

30 Journaled in the extremity of the casing remote from the rock spindle 9, is a roller 32 which engages the opposite runs of the flexible strop 33, and forms a guide to keep the runs of the strop separated and whereby these runs are maintained in parallel, or approximately parallel, relation.

Assuming that the parts are assembled, substantially as indicated in Figs. 1 and 2, and it is desired to sharpen a blade 20, the 40 latter is applied to the holder 21, after which this holder is inserted in the spindle 17, the blade protruding through the slots formed in the blade, as heretofore explained, and as illustrated in Figs. 3 and 4. I will 45 also assume that the flexible strop 33 is applied to the instrument, as shown in the drawing, and also that one end of the casing is equipped with holding means, as chains 34, which are connected with the casing by rings 35 and with each other by a ring 36. Now, if these chains are passed around a hook, or other stationary object of sufficient stability to resist the pull upon the strop, the latter may be moved back and forth by alternately pulling upon its opposite extremities. When the strop is pulled in one direction, the operating spindle is given a partial rotary movement which, through the medium of the crank arms 12 50 and 15, communicates a similar movement but in the opposite direction to the spindle 17 carrying the blade-holder 21 whereby a corresponding movement is imparted to the blade, throwing its opposite edges into contact with the opposite runs of the strop for

sharpening purposes; then, as the movement of the strop is reversed, the two rock spindles are actuated in directions the reverse of their previous movement, thus bringing the opposite edges of the blade into contact with the 70 opposite runs of the strop, whereby both sides of each edge are brought into a sharpening engagement with the strop. This operation is continued until the blade is sharpened. As soon as the actuating pull 75 upon the strop ceases to act, the blade-holder together with the spindle in which it is located, is automatically thrown by the spring 30 to the central position whereby the blade occupies a position parallel, or approximately parallel, with the two runs of the strop. This prevents the cutting of the strop when its movement is reversed, before the edges of the blade have time to change their position.

In order to facilitate the removal and insertion of a blade, the casing is provided at one end with an elongated opening 40, which is enlarged at the center to receive the hollow spindle 17. This slot 40 permits the introduction of the blade-holding pin, or spindle 21, with a blade in position, as illustrated in Figs. 10 and 11. This makes it practicable to quickly introduce a blade for sharpening purposes and remove it after it 95 has been sharpened, and is therefore considered a very important feature in a device of this class.

Having thus described my invention, what I claim is,

1. A razor sharpener comprising a casing, a spindle journaled in the casing, a strop engaging the said spindle, and a second spindle journaled in the casing and slotted on opposite sides, means for normally retaining the second spindle in a predetermined position, a holder for the blade adapted to be inserted in the last named spindle which is hollow, the opposite edges of a double edged blade protruding through the slots in the spindle, substantially as described.

2. A razor sharpener comprising a casing, a spindle journaled in the casing, a razor strop passing around and engaging the spindle in operative relation, a second spindle journaled in the casing to receive a double edged blade, means for normally retaining the second spindle in a predetermined position, and an operative connection between the journal of the first named spindle and that 115 of the blade-holding spindle, whereby as the strop is moved back and forth over the first named spindle, the blade is actuated for sharpening purposes.

3. A razor sharpener comprising a casing, 125 two rock spindles journaled in the opposite sides of the casing, a holder adapted to receive a double edged blade, the said blade-holder being inserted in the one spindle which is hollow for the purpose, the last 130

named spindle being slotted on opposite sides to allow the opposite edges of the blade to protrude, an operative connection between the two spindles, a flexible strop 5 adapted to engage the other spindle, and a spring for normally retaining the blade-carrying spindle in such position that the blade will be parallel, or approximately parallel, with the runs of the strop, substantially as described.

4. The combination with a casing, of a rock spindle journaled in the casing, a flexible strop engaging the said spindle, a second spindle slotted on opposite sides and adapted 15 to receive a double edged blade, the last named spindle being provided with a lip, springs engaging the lip on opposite sides and normally holding the second spindle in such position that the blade is parallel, or 20 approximately parallel, with the runs of the strop, the opposite extremities of the two spindles being provided with crank arms connected in operative relation whereby as the one spindle is actuated the other is simultaneously operated, substantially as described.

5. In a razor sharpener, the combination with a casing, of a blade-holding spindle journaled in the casing, the blade being double edged and protruding through slots formed in the said spindle, means for normally maintaining the blade-holding spindle in a predetermined position, another spindle journaled in the casing, a flexible strop engaging the last named spindle, an operative connection between the two spindles, and a guide roller engaging the opposite runs of the sharpening strop, substantially as described.

40 6. A razor sharpener comprising a casing, a spindle journaled in the casing, a strop engaging the said spindle, a hollow spindle journaled in the casing and slotted on opposite sides, a holder for the blade adapted to 45 be inserted endwise in the hollow spindle,

the opposite edges of a double-edged blade protruding through the slots in the hollow spindle, substantially as described.

7. A razor sharpener comprising a casing, a spindle journaled in the casing, a strop engaging said spindle, a hollow spindle also journaled in the casing and slotted on opposite sides, a blade holder consisting of a pin adapted to be inserted endwise in the hollow spindle and readily removable therefrom in an endwise direction.

8. A razor sharpener, comprising a casing, a spindle journaled in the casing, a strop engaging the said spindle, a hollow spindle journaled in the casing and slotted on opposite sides, a holder for the blade, said holder comprising a pin adapted to enter the hollow spindle in an endwise direction, the casing being slotted at one end to permit the introduction of the blade-holder with the blade in place, the opposite edges of a double-edged blade protruding through the slots in the hollow spindle when the blade is inserted, substantially as described.

9. A razor sharpener, comprising a casing having an elongated opening in one end, a spindle journaled in the casing, a strop engaging said spindle, and a blade-holder adapted to enter the casing in an endwise direction with a blade in place, the blade-holder being journaled in and readily removable from the casing, and an operative connection between the spindle and the blade-holder, whereby as the spindle is moved back and forth, the blade-holder is rotated in reverse directions to bring both edges of the blade into engagement with the strop, substantially as described.

In testimony whereof I affix my signature in presence of two witnesses.

JOHN J. MEEHAN.
